UNITED STATES PATENT OFFICE.

LEWIS R. WALLACE, OF WALTHAM, MASSACHUSETTS, ASSIGNOR TO NEVENS-WALLACE
TRAIN CONTROL COMPANY, A CORPORATION OF MASSACHUSETTS.

TRAIN-STOP MECHANISM

1,269,662.

Specification of Letters Patent. Patented June 18, 1918.

Application filed May 26, 1914. Serial No. 841,054.

To all whom it may concern:

Be it known that I, LEWIS R. WALLACE, a citizen of the United States, residing at Waltham, county of Middlesex, Commonwealth of Massachusetts, have invented certain new and useful Improvements in Train-Stop Mechanism, of which the following is a specification.

This invention relates to the positive control of railroad trains and the like for the purpose of preventing the neglect or disobedience of the usual signals employed in such systems. The invention is particularly adapted to be used in block systems where trains are to be kept absolutely within certain limits although obviously capable of other use.

The object of my present invention generally stated is to provide an improved train stop mechanism which will positively control the movement of railroad trains within certain block limits.

More specifically this invention has for its object to provide for the positive locking of the track tripper in safety position until such a time as it shall be necessary for the tripper to come to danger position, for positively setting the trip at danger, and for positively resetting the trip to safety after it has been actuated.

30 It has been calculated.
The construction and operation of my in-
vention will be more fully disclosed in the
specification that follows. In the drawings
35 forming a part of that specification I have
shown as an illustrative embodiment a con-
struction which not only clearly illustrates
the principles involved but is in itself a form
which has proven satisfactory in actual use.
Throughout specification and drawings like
40 reference numerals are correspondingly ap-
plied, and in these drawings:

Figure 1 is a plan view of a track box and associated parts in accordance with my invention.

45 Fig. 2 and Fig. 3 are longitudinal sections on the lines 2—2 and 3—3 respectively of Fig. 1.

Fig. 4 is a view similar to Fig. 2 showing the trip in danger position.

50 Fig. 5 is a face view of the locking device.

Fig. 6 is a vertical section through the box, and

Fig. 7 is a diagrammatic view of the installation.

55 I have indicated at 1 a track box located

at or near the entrance of a track section or block under automatic signal control. The box is supported adjacent a rail R between two ties T by the end flanges 2 of the box, which flanges rest flat on the ties and are 60 secured thereto. The box has lateral flanges 3 to which a suitable cover is secured.

Journalized in suitable bearings near one end of the box is a transverse rock shaft 4 to which is rigidly fastened externally of the box a trip actuating pawl 5 positioned to one side of the rail and normally in depressed or non-interfering relation to a trip arm carried by the engine. The pawl is locked in depressed or safety position by an electrically controlled locking mechanism. The control circuit for this locking mechanism is included in the relay circuit for the track and automatic block signals. This last named circuit is dominant and controls the pawl simultaneously with the semaphore arms of the block signals.

The pawl locking mechanism and control circuit therefor will first be described. Mounted on the rock shaft 4 between its 80 ends and wholly inclosed within the track box is a weight 6 effective when properly supported at its free end to maintain the pawl in safety position. The free end of the weight 6 has an extension 7 normally supported on the spring latch end 8 of an arm 9. The arm 9 is pivoted between its ends on a transverse pivot pin 9¹ mounted in a bearing plate 11 rising from the floor of the track box. The opposite end of the arm 9 is pinned to the bifurcated end of a lever 10. The other end of the lever 10 is connected by a link 11¹ to a second lever 12 pivoted at its lower end in brackets 13 rising from the floor of the track box. To the 95 upper end of the lever 12 a longitudinally

upper end of the lever 12 a longitudinally movable locking arm 14 is pinned. The arm 14 is guided in the bearing plate 11 and has a locking notch 15 adapted to coöperate with a locking dog 16 carried by an armature 17. The armature 17 is pivoted on the pin 9¹ and is normally held against the cores of a pair of electro-magnets 18 suitably supported within the box and wired up in the control circuit, which is normally closed. When the magnets are energized the tendency of the armature is to hold the dog in rigid erect locking relation with the notch 15. When so held the dog is virtually supporting the weight 6. When the mag- 110

2

nets are deenergized by a break in the circuit the armature is released. The dog is then no longer forced into locking engagement with the notch 15 but is free to tilt downwardly and disengage from the notch. 5 The support for the weight 6 being thus removed, the weight is now free to descend by gravity until it stops against the abutment 6¹ rising from the floor of the box. In its descent the weight swings the latch end 8 of the arm 9 down, tilting up the opposite end of said arm. This raises the lever 10 which through the link 11¹ and the lever 12 draws the arm 14 back until the notch 15 thereof is withdrawn from its locking engagement with the dog. The descent of the weight rocks the pawl 5 up into danger position. As soon as the weight drops past the latch end 8, the dog 16 tilts back to 20 erect position so as to be ready to engage the notch 15 when the arm 14 is brought back to locking position.

The control circuit for the locking mechanism is normally closed and the electro- 25 magnets energized. A simple form of circuit is illustrated in Fig. 7 in which a lead wire 19 connects a binding post 19¹ on one of the electro-magnets with one pole of the track battery B. The other leg of the circuit is completed from the binding post 19² of the other electro-magnet by a lead wire 20 into which the automatic block signal circuit may be cut in at any point and a relay 21 connecting with the other pole of the 30 battery. The locking circuit just described is subject to the dominating circuit for the block signals.

The resetting mechanism for the pawl and associated parts is controlled from the 35 locking circuit by a shunt circuit from the electro-magnets. This circuit in its simplest form may consist of a wire 22 from the binding post 19² to a short contact 23 and a wire 24 from a longer contact 25 to the binding post 26 of a resetting motor 27 disposed within the track box. The circuit is completed from the other binding post 28 of the motor to the other binding post 19¹ of the electro-magnets by a wire 29. The 40 purpose of this circuit is to control the resetting mechanism for the pawl. This circuit is normally open and is only put in condition to be closed when the weight 6 descends. As before seen this weight descends 45 only when the magnets are deenergized. The circuit for the resetting mechanism is therefore not closed until the magnets are again energized.

The resetting circuit is maintained normally open by the contacts 23 and 25 and the weight 6. The free end of the longer contact 25 normally contacts with the top face of the weight when said weight is in the supported position of Fig. 3. When 50 so disposed the contact 25 is spaced from

the contact 23 by the weight. When the weight descends by reason of the deenergization of the electro-magnets and the consequent withdrawal of the support for the weight, the contact 25 springs down against 55 the contact 23. This places the shunt circuit in condition to become effective when the current comes on again and the magnets are again energized. As soon as the break in the dominant block signal circuit is closed 60 and the magnets energized again, the shunt circuit will be closed causing the motor 27 to revolve to reset the weight to its original position. This is effected through a worm 65 30 on the motor shaft meshing with a gear 31 on a counter-shaft 32. The rotation of the shaft 32 is transmitted to the weight to raise the same by a gear 33 meshing with a large gear 34 on a second shaft 35. The gear 34 has near its periphery a laterally projecting cam surface 36 adapted to engage a cam roll 37 on the weight during a part of the rotation of said gear. The cam 36 and roll 37 are so positioned relatively as to cause the weight to be lifted only far enough 70 to pass the latch end 8 of the locking arm 9, which end yields inwardly to permit the weight to pass, but automatically assumes supportive position as soon as the weight has passed. The action is so timed that as 75 soon as the weight passes the latch end the cam has moved past the roll and the weight is no longer being positively raised. The weight continues upwardly however by its own momentum until it contacts with the 80 long contact pen 25, lifting said pen away from the pen 23, thereby breaking the circuit and stopping the motor. During this 85 action the electro-magnets which were energized as soon as the current came on 90 and the motor started to revolve, have drawn up the armature and with it the dog 16, thereby engaging the dog with the locking notch 15 and locking the weight in raised position. The movement of the weight upwardly rocks the pawl 5 downwardly and 95 out of the influence of the trip arm carried by the engine.

In use the pawl is normally locked in safety position. As soon as a train enters 100 the block which the pawl is protecting, the circuit is broken and the weight 6 released, thereby rocking the pawl up to danger position. The pawl will remain in this position so long as the train is in the block and the circuit broken. Assuming that a train 105 is already in the block and the pawl set in danger position, the pawl will strike the trip arm on the engine of a train following, which is attempting to enter the block and 110 will cause an application of the air brakes. This mechanism for setting the air brakes may be of any desired type. After the pawl 115 has struck the trip on the engine it continues to remain up until the train already in the 120

block has passed out and the circuit is again closed. As soon as the circuit is closed the magnets are energized again and the resetting apparatus becomes effective to restore

5 the weight and trip to the original position.

While I have shown and discussed my present invention as applied to the block signaling system of a railroad I would 10 have it understood that I do not limit myself to this use but reserve the right to apply the principles in any situation where the same would be found practicable.

Various modifications in the form and 15 construction of my device may obviously be resorted to within the limits of the appended claims.

What I therefore claim and desire to secure by Letters Patent is:

20 1. In train stop mechanism, an oscillatable track stop, a counter-balance therefor, a pivoted arm having a normal supporting relation to said counter-balance, a locking arm operatively connected with said sup-

25 porting arm, a pivoted dog adapted for locking engagement with said locking arm to normally maintain said supporting arm in supporting position relative to the counter-balance, and an electro-magnetic mechanism normally maintaining the locking engagement of said dog with said locking arm.

30 2. In train stop mechanism, a rock shaft, a track obstacle thereon adapted for oscillation in the vertical plane, a counterbalance 35 for said obstacle mounted on said shaft and disposed in the direction opposite to that of the track obstacle, a pivoted arm having a spring latch at its free end normally disposed for supporting engagement with said 40 counterweight, a pair of operatively connected levers associated with said arm, a locking member fastened to one of said levers, a locking dog pivoted on the pivot for

said first named arm and adapted for locking engagement with said locking member, 45 an armature carrying said dog and an electro-magnet for said armature.

3. In train stop mechanism, a track obstacle having a position of interference and a position of non-interference with relation 50 to a train-carried air-brake relief actuator, a gravity operating member controlling the position of said track obstacle and having a supported and a non-supported position, an electro-magnetic supporting mechanism controlled by the condition of the track ahead 55 for maintaining said gravity member in supported position, a resetting circuit subject to said electro-magnetic mechanism for restoring said gravity member to supported 60 position only when said supporting mechanism is in condition to support the same, a motor included in said circuit, and a rotatable member driven by said motor and having an element thereon disposed for resetting engagement with a portion of said gravity member during a part of the revolution of said rotatable member.

4. In train stop mechanism, a track obstacle having a position of interference and 70 a position of non-interference with relation to a train-carried air-brake relief actuator, a gravity operating member controlling the position of said track obstacle and having a supported and a non-supported position, a 75 cam roll on said gravity member, a restoring mechanism for said gravity member including a rotatable resetting member having a cam disposed for resetting engagement with said cam roll of the gravity member.

80 In testimony whereof I affix my signature in presence of two witnesses.

LEWIS R. WALLACE.
